DESIGN FOR A BOX

Frank McIntosh, New York, N. Y., assignor to Lenthalic Incorporated, New York, N. Y., a corporation of New York

Application April 5, 1940, Serial No. 91,491

Term of patent 3½ years

To all whom it may concern:

Be it known that I, Frank McIntosh, a citizen of the United States, residing at New York city, in the county of New York and State of New York, have invented a new, original, and ornamental Design for a Box, of which the following is a specification, reference being had to the accompanying drawing, forming part thereof.

In the drawing:

Figs. 1, 2, and 3, respectively, are top, front, and rear views of a box embodying my new design.

The straight lines on the bows and small circles represent differentiating colors; other lines represent shading.

I claim:

The ornamental design for a box, substantially as shown and described.

FRANK McINTOSH.
